COMBINED ELECTRIC MOTOR DRIVEN CENTRIFUGAL PUMP AND INLET SCREEN THEREFOR AND THE LIKE

Charles B. Faison, Oklahoma City, Okla., assignor to Little Giant Corporation, Oklahoma City, Okla., a corporation of Oklahoma

Original application Nov. 26, 1963, Ser. No. 77,578, now Design Patent No. 201,529, dated June 29, 1965. Divided and this application Aug. 31, 1964, Ser. No. 81,725

Term of patent 14 years

(Cl. D65—1)

FIGURE 1 is a front perspective view of a combined electric motor driven centrifugal pump and inlet screen showing my new design;

FIGURE 2 is a front elevational view thereof;

FIGURE 3 is a rear perspective view of the screen element separated from the pump for convenience of illustration; and

FIGURE 4 is a bottom plan view.

This application is a division of my prior copending application Serial No. D.77,578 filed November 26, 1963.

I claim:

The ornamental design for a combined electric motor driven centrifugal pump and inlet screen therefor and the like, as shown.
